UNITED STATES PATENT OFFICE.

WILLARD D. RICHARDSON, OF COLUMBUS, OHIO.

METHOD AND APPARATUS FOR BURNING CLAYWARE.

Application filed September 16, 1924. Serial No. 738,090.

My invention relates to method and apparatus for burning clay ware, and has to do particularly with the burning of clay ware in continuous tunnel kilns and the control and distribution of combustion gases in the high temperature firing zone of such tunnel kilns.

In the past, in burning clay ware in continuous tunnel kilns, it has been the practice to create a longitudinal draft in the tunnel by means of a fan at or near the receiving end of the tunnel whereby the hot combustion gases in the furnace will pass over and through the top and sides of the tunnel in the space between the ware on the cars and the crown and sides of the tunnel. Due to this longitudinal draft hitherto produced in these continuous tunnel kilns, the combustion gases, after passing the firing zone, come in contact with the ware in the water-smoking zone with the result that the sulphurous gases of combustion are condensed by the moisture from the ware at low temperatures forming sulphuric acid which acts upon certain bases in the clay, changing them to soluble sulphates, which produce scumming and discoloration of the ware and has also been the cause of much damage to glazes. Furthermore, in burning clay ware in this type of tunnel kiln, the ware on the outer end top parts of the setting is burned to a different degree than the ware on the interior of the setting, with the result that a large amount of the burned ware is defective either from overburning in the top and outer portions of the setting or from underburning in the central bottom portion.

My invention has to do primarily with the method of passing the hot gases of combustion in contact with the ware only in the firing zone section of the continuous tunnel kiln and of preheating the air for combustion by radiation in the cooling zone of the tunnel and of preheating the ware in the preheating zone by radiation from the products of combustion in the firing zone. This method of burning ware in a continuous tunnel kiln results in an even degree of burning of the ware by the hot gases of combustion in the firing zone and prevents scumming, discoloration or other damage to the ware in the water-smoking and oxidation zones of the kiln. This novel method of burning clay ware is accomplished by the provision of a continuous tunnel

kiln having specially constructed furnaces and draft outlets in the firing zone for producing a positive cross draft of the hot gaseous products of combustion through the lower part of the car of ware being burned in combination with suitable conduits in, or adjacent, the walls of the tunnel in both the preheated zone and cooling zone.

One of the objects of my invention is the provision of a tunnel kiln which is continuous and which is provided with a firing zone having furnaces alternately positioned on either side thereof and exhaust draft outlets positioned in the walls of the tunnel opposite such alternately positioned furnaces. The result of this arrangement is that the hot gases of combustion from the furnaces will pass directly across the tunnel through flues in the car and the ware setting and into the draft outlets whereby the bottom portion of the ware on the cars is heated to the desired temperature without overheating the ware at the top of the car setting.

Another object of my invention has to do with the provision in a tunnel kiln of a plurality of ware carrying cars for passing continuously through such tunnel and a blower at the discharge end of the tunnel for forcing air to be heated by the hot ware in the cooling zone of the kiln to the furnaces for combustion of the fuel; said blower to also force air to be heated by the hot ware in the cooling zone into the water-smoking and preheating zone for circulation therein. Also an exhaust fan at the receiving end of the tunnel for the movement of the combustion gases through radiating pipes in the preheating zone but without any longitudinal draft through the tunnel from the firing zone.

A further object of my invention contemplates the provision of a continuous tunnel kiln having preheating, firing and cooling zones and passages in the walls of the tunnel extending to all three zones for controlling the distribution of gases and heat in such various zones.

Another object of my invention is the provision of a continuous tunnel kiln, a series of ware carrying cars adapted to pass substantially continuously through said tunnel kiln and a series of zones through which said ware carrying cars pass; the cars in one zone being subjected to a radiating heat for preheating the ware; the cars in another zone

being subjected to hot combustion gases passing through the ware in a direction at right angles to the movement of the cars; and the cars in another zone being subjected to a cooling action whereby the heat radiated in the cooling process is utilized for preheating the air to be used for combustion and for supplying hot air for circulation in the preheating zone.

10 Various other features of my invention will be apparent as this description progresses and will be brought out in the claims appended hereto. The various objects of my invention may be obtained by 15 the structure illustrated in the drawings, wherein similar characters of reference designate corresponding parts and wherein:

Figure 1 is a cross sectional plan view of a portion of my continuous tunnel kiln 20 structure including the preheating and a portion of the firing zone and showing the manner of arranging the furnaces and draft outlets in the firing zone and the manner of conducting the exhaust gases from the firing 25 zone into the preheating zone.

Figure 2 is a cross sectional plan view similar to Figure 1 and showing the other end of my novel tunnel structure including a portion of the firing zone and the cooling 30 zone and also illustrating the manner of utilizing the heat in the cooling portion of the continuous tunnel to preheat the air used for combustion.

Figure 3 is a vertical central longitudinal 35 section of the structure shown in Figure 1 and showing the arrangement of the furnaces and draft outlets in the wall of the firing zone, the conduits for conducting preheated air to the furnaces and the products 40 of combustion from the furnaces and the means for conducting the products of combustion from the tunnel without producing a longitudinal draft therein.

Figure 4 is a vertical central longitudinal 45 section of the structure shown in Figure 2 and showing in particular the flues for conducting air through conduits in and adjacent the walls of the cooling zone of the tunnel whereby the air is preheated prior to 50 combustion without causing a longitudinal draft in the cooling zone.

Figure 5 is a vertical cross section taken on line 5—5 of Figures 1 and 3 and showing a ware carrying car passing through the 55 tunnel and conduits or radiating pipes arranged adjacent the walls in the preheating zone of the tunnel for preheating the air by radiation.

Figure 6 is a vertical cross section taken 60 on line 6—6 of Figures 1 and 3 and showing in detail the relative arrangement of the furnaces, cars and draft outlets in the firing zone.

Figure 7 is a vertical cross section taken 65 on line 7—7 of Figures 2 and 4 and illus-

trating the manner of conducting the preheated air from the cooling zone to the furnaces in the firing zone.

Figure 8 is a vertical cross section taken on line 8—8 of Figures 2 and 4 and showing the arrangement of conduits or pipes in the cooling zone of the tunnel for preheating and conducting the air to the furnaces and also showing the manner of arranging a space in the top of the tunnel for producing 75 hot air available for drying or water-smoking.

Figure 9 is a detail perspective view, partially cut away, of a portion of the firing zone of my continuous tunnel kiln and showing the location and arrangement of the furnaces, draft outlets and flues for conducting the preheated air to and the products of combustion from the firing zone.

In the drawings, and referring particularly to Figures 1 and 2, my tunnel kiln is shown as comprising a continuous tunnel, which, on account of its peculiarities of construction, may be divided into three sections or zones. These zones may be called the 85 preheating zone, the firing zone, and the cooling zone and may be designated by the numerals 1, 2, and 3, respectively. The ware to be treated is passed through the tunnel and through the three zones by means 90 of a series of cars 4 which are designed to be run upon suitable tracks 5 which extend throughout the length of the tunnel. These cars may be of any desired design. In the 95 preferred form of my invention, I desire to provide each car with a series of transverse supporting members 6 which are so spaced apart as to permit a free passage of gases between them and which are also so spaced as to provide a foundation for the ware 100 upon the car.

It will be understood that in this type of kiln the cars are moved slowly and continuously through the entire kiln and that as one car is moved into the preheating zone of the kiln, another car is removed from the cooling end of the kiln. No particular mechanism is shown for advancing the cars through the tunnel and any type of mechanism may be utilized for this purpose. In 115 Figure 3, I have shown a car 4 in position ready to be advanced towards the preheating zone proper of the tunnel kiln and I have also shown a pusher rod structure 7 which may be utilized in advancing the cars 120 into and through the tunnel.

As is best shown in Figures 5 to 9, the tunnel is provided with suitable troughs 8 which extend throughout the tunnel. These troughs are preferably filled with sand. Suitable flanges 9 extending downwardly from each side of the cars are designed to enter these sand troughs and thus provide a seal to prevent the circulation of hot gases 125 beneath the car platform.

The preheating portion 1 of the tunnel is provided with a plurality of horizontal flues which are arranged vertically on each side of the tunnel and between the ware upon the cars and the walls of the tunnel. These flues may be designated 10 and extend from a point adjacent the firing zone of the tunnel to suitable outlet conduits 11 at the entrance of the preheating zone. These outlet conduits 11 form the connecting means between an exhaust fan 12 and the flues 10. These multiple flues 10 are preferably constructed of socketed refractory pipes of good conductive and radiative qualities in the hotter portion of the reheating zone, near the firing zone, and are constructed of cast iron pipes of the same cross section in the cooler portion of the reheating zone near the entrance or receiving end of the tunnel. These refractory flues and cast iron flues are continuous, with expansion joints in every unit of pipe. In general, these flues 10 are designed to conduct all of the products of combustion from the firing zone to the exhaust fan 12 where they are exhausted to the atmosphere. Also, they conduct heat through their walls and radiate heat to the ware in the tunnel.

The central portion of my tunnel kiln, which may be designated the firing zone, is best illustrated in Figures 1, 6 and 9. This portion of the tunnel is provided with side walls which may preferably extend fairly close to the ware upon the car and a crown 13 which is symmetrical with the crown which extends throughout the preheating zone. Each wall of the tunnel in the firing zone is provided with a series of alternately positioned furnaces 14 and draft outlets 15. Each furnace on one side of the firing zone wall is directly opposite the draft outlet on the opposite wall. Each wall of the tunnel in the firing zone is provided with draft collecting chambers 16 which chambers are connected to the draft flues 17 and have such connections regulable by means of suitable dampers 18 which may be, in turn, controlled by means of suitable handles, as best shown in Figure 9, for controlling the effectiveness of the draft induced by the exhaust fan 12. The air for combustion in the furnaces 14 is preheated in the cooling zone and conducted to the furnaces by means of suitable flues 19 located at the bottom walls of the firing zone of the tunnel. The amount of air for combustion which is introduced into the furnaces 14 may be controlled by the dampers 20 which may be operated in a similar manner to the dampers 18. Although I have shown the furnaces 14 as being provided with oil burners, it will be understood that any form of fuel may be utilized and combustion obtained by introducing the air through the flues 19. The air for the combustion of the fuel in the furnaces 14 is conducted to the flues or ducts 19 by means of suitable pipes or conduits 21 which extend along the side walls of the cooling portion of the tunnel, as best illustrated in Figures 4 and 8. The air is supplied to and forced through these pipes or conduits 21 by means of a suitable blower 22 positioned adjacent the discharge end of the tunnel. It will be obvious that the air in passing through these pipes 21 will be heated by the heat stored in the cooling zone of the kiln and in the burnt ware.

The entrance end of the tunnel is provided with a suitable sealing means or door 23 and the discharge end of the tunnel is likewise provided with a suitable sealing means or door 24.

In the normal operation of my continuous tunnel kiln, the cars 4 are moved forwardly from left to right in Figures 1 to 4, by the addition of each individual car or a series of cars at the entrance and the exit of a like number of cars at the discharge end of the tunnel. Thus, all of the cars throughout the tunnel and in each zone will be simultaneously moved forward with the addition of each car in the preheating zone. The air for combustion may be drawn from the discharge end of the tunnel through the pipes 21 and flues 19 to the furnace, or may be forced through such pipes and flues by the blower 22, the air being preheated by the heat stored in the cooling zone of the kiln and in the burnt ware. This preheated air will pass along through the flues 19 and will be forced upwardly into the furnaces 14 to combine with the oil or other fuel to produce combustion within such furnaces. The exhaust fan 12 will then cause the hot gases of combustion in the furnaces to pass directly across the tunnel towards and through the draft outlets 15 and into the draft collecting chamber 16. The hot gases passing directly from the furnaces to the draft outlets will obviously pass between the ware supports 6 and through the ware in the bottom portion of the cars so as to heat such ware to the desired temperature without overheating the ware at the top of the car. Each furnace with its opposite draft flue forms a means of generating hot gases, and so the ware passes through a series of hot gases while moving through the firing zone of the tunnel. It will also be obvious that the natural tendency of the hot gases of combustion is to rise toward the top of the tunnel but this positive induced draft can be regulated by the dampers 18 so as to cause a sufficient portion of the hot gases to pass directly and transversely between the furnaces 14 and the draft outlets 15. Controlled by the size of the opening made by the dampers 18, the products of combustion will pass up into the draft flues 17 on either side of the furnace and then into the multiple series of pipes or

conduits 10 which run along the side walls of the tunnel forming the preheating zone. In this zone the conduits 10 will abstract the heat from the gases by conduction and radiation and the ware upon the cars in the preheating zone will be initially heated by the radiation from such conduits 10 and by connection of the hot air from the cooling zone.

10 Referring particularly to Figures 4 and 8 it will be seen that I have provided a chamber 25 in the crown of that portion of the tunnel designated the cooling zone. This chamber 25 extends from the discharge end 15 of the tunnel to a point adjacent the firing zone. Cast iron plates 26 may serve to separate the chamber 25 from the main portion 3 of the cooling zone. Fresh air entering this chamber 25 will be heated by radiation 20 of heat from the ware in the cooling zone. This heated air may then be conducted through suitable conduits 27 (see Figure 2) to the preheating zone 1. Thus the air in the preheating zone may be heated by radiation 25 of heat from the products of combustion from the firing zone and also heated and dried directly by heated fresh air from the chamber 25. As the clay ware must be dry before entering the tunnel, some or all 30 of this preheated air in the chamber 25 may be conducted to a suitable drying or water-smoking kiln to dry and preheat the green ware.

It will be seen that I have provided a novel 35 and very simple tunnel kiln for treating and burning clay ware without setting up longitudinal drafts from the firing zone in any part of the tunnel kiln. It will further be noted that I have provided a tunnel kiln 40 which, while continuous, is divided into three zones, namely, a preheating zone, a firing zone, and a cooling zone and which tunnel is so constructed that the ware in the preheating zone is not subjected to any longitudinal drafts from the firing zone or to 45 sulphurous gases but which are merely preheated by radiation and convection. Furthermore, the tunnel adjacent the firing zone is so constructed that a sufficient amount of 50 the hot gases are passed directly and transversely across the lower portion of the tunnel and through the bottom portion of the ware upon the car. It will still further be seen that the air for combustion instead of 55 being preheated by passing directly over the ware in the cooling section, is preheated by passing such air through radiating chambers or ducts which are heated by the ware in the cooling section.

60 It will be understood that the chamber 25 for the preheating of the fresh air to be used in the preheating zone or water-smoking kiln may be constructed in such a manner that the chambers would extend down 65 on each side of the tunnel or the chamber 25

as illustrated in Figures 4 and 8 may extend the entire length of the crown of the tunnel whereby the fresh air may be preheated both in the cooling and firing zones and then conducted directly in the preheating zone. 70

It will also be understood that the height of the arch over the furnace throat may be varied for different products as may be further necessary to secure the uniform burning of the ware during the continuous movement of the cars through the firing zone.

It will be further understood that the preheating, firing, and cooling portions or zones of my tunnel kiln may be constructed of various lengths and sizes to accommodate 80 various sizes of cars and ware sections and various numbers of cars.

Having thus described my invention, what I claim is:

1. The method of burning clay ware in 85 tunnel kilns which comprises subjecting the ware to a series of hot gases which move in opposite directions transversely of the tunnel.

2. The method of burning clay ware in 90 tunnel kilns which consists in subjecting the ware on the conveying units to hot gases which pass from furnaces in both walls of the tunnel, through the ware on the units and into draft flues opposite said furnaces 95 in opposite directions and at right angles to the direction of movement of the conveying units.

3. The method of burning clay ware in 100 tunnel kilns containing preheating and firing zones, which consists in passing hot gases transversely through the ware setting in the firing zone and then utilizing these hot gases to heat the air in the preheating zone by radiation. 105

4. The method of burning clay ware in 110 tunnel kilns containing preheating and firing compartments, which consists in passing the hot gases from one wall of the tunnel to the other wall in the firing zone and subjecting the ware only in such firing zone to the direct contact of said hot gases.

5. The method of burning clay ware in 115 tunnel kilns which comprises preheating the air for combustion by heat radiated from the ware, combining this preheated air with fuel, passing the hot gases transversely of the furnace to treat the ware and then preheating the ware at the entrance of the tunnel by radiation from the products of combustion. 120

6. A car tunnel kiln comprising a firing zone for directing combustion gases upon and through the ware and outlets provided only in such firing zone of the kiln for conducting the combustion gases therefrom. 125

7. A car tunnel kiln having a firing zone with furnaces on both sides of the tunnel, draft flues in both walls of the tunnel, and draft ports from the tunnel into these long- 130

gitudinal draft flues directly opposite every furnace.

8. A car tunnel kiln having single longitudinal flues in the outside walls of the tunnel in the firing or high-temperature zone and multiple longitudinal draft flues within the tunnel in the preheating zone.

9. A car tunnel kiln comprising a firing zone, furnaces therein and recesses extending from the inner wall of the tunnel opposite each furnace in the firing zone and ports or outlets from these recesses into a draft-collecting chamber.

10. A car tunnel kiln having recesses in the inner wall of the tunnel opposite each furnace in the firing zone, outlets from these recesses to a draft-collecting chamber, and dampered outlets from each of such chambers to a main longitudinal draft flue in each wall of tunnel.

11. The method of burning clay ware in tunnel kilns which comprises preheating air by radiation in the cooling zone and then conducting such preheated air directly into the preheating zone.

12. The method of burning clay ware in tunnel kilns which comprises preheating both the air for combustion in the firing zone and air for drying in the preheating zone by radiation in the cooling zone.

13. Tunnel kiln structure for burning clay ware comprising means for heating the air for combustion by radiation, means for heating a separate chamber of air by radiation and means for conducting the preheated air to the firing zone and preheating zone.

14. A tunnel kiln comprising pre-heating, burning and cooling zones, said burning zone having alternate furnaces and draft

flues arranged in each side, the furnaces in each side being arranged substantially opposite the draft flues in the other side.

15. The method of burning clay ware in tunnel kilns which consists in subjecting the ware upon the conveying cars to hot gases from furnaces in the sides of the tunnel which pass through the ware setting to draft flues opposite the respective furnaces.

16. Tunnel kiln structure for burning clay ware having a firing zone, furnaces arranged alternately in opposite walls of said firing zone, and draft flues arranged opposite said furnaces.

17. The method of burning clay ware in tunnel kilns having preheating, burning, and cooling zones, which comprises preheating air by radiation in the cooling zone, using such preheated air for combustion of fuel in the firing zone, passing the products of combustion through the ware setting transversely of the kiln, and then collecting such products of combustion and utilizing them for heating the preheating zone by radiation.

18. The method of burning clay ware in tunnel kilns which comprises heating the ware with hot gases which pass from furnaces on each side of the tunnel to oppositely disposed draft flues in opposite directions.

19. A tunnel kiln comprising preheating, burning and cooling zones, furnaces in said burning zone and draft flues opposite said furnaces in the firing zone and outlet ports from these draft flues communicating with radiators in the preheating zone.

In testimony whereof I hereby affix my signature.

WILLARD D. RICHARDSON.
